UNITED STATES PATENT OFFICE.

FREDRICK W. KALLUSCH, OF LONG BEACH, CALIFORNIA.

APPARATUS FOR SUPPLYING HUMIDIFIED AND SCENTED AIR.

1,121,845.

Specification of Letters Patent. Patented Dec. 22, 1914.

Application filed May 5, 1914. Serial No. 836,519.

To all whom it may concern:

Be it known that I, FREDRICK W. KALLUSCH, a citizen of the United States, residing at Long Beach, in the county of Los Angeles and State of California, have invented a new and useful Apparatus for Supplying Humidified and Scented Air, of which the following is a specification.

The present invention appertains to an apparatus for supplying air to the rooms of residences, hospitals, and the like, and aims to provide a novel and improved apparatus of that nature, for furnishing humidified and scented air which will have cooling, curative, or other beneficial properties.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:

Figure 1 is a sectional view of the improved apparatus, portions being shown in full. Fig. 2 is a sectional view of the water tank or reservoir with the partition or shelf and basket removed. Fig. 3 is a cross section of the tank or reservoir, taken on the line 3—3 of Fig. 1.

In carrying out the present invention, there is provided a suitable tank or reservoir 1, which is provided with a removable top or cover 2. The tank or casing 1 may be supported in any suitable manner, such as in the cellar of the building to which the apparatus is applied, or at any other suitable locality. The cover or lid 2 of the tank 1 may be removably attached thereto in any well known manner. The ends of the tank 1 are provided with inlet and outlet openings, formed by notches or seats 3 provided in the ends of the tank 1, and complementing notches or recesses 4 provided in the ends of the cover 2. To the ends of the tank 1 are secured suitable seat members or brackets 5, upon which may be seated, a removable partition or shelf 6. The seat members 5 are disposed directly below the openings 3—4, to thereby support the partition 6 approximately flush with the lower ends of the said openings. A

meshed wire or reticulated basket 6' is suspended from the cover 2, the upper edges of the ends of the basket having curved lips or flanges 6^a which are engageable in curved keepers 6^b secured to the bottom of the cover 2. The basket 6' is preferably curved or concaved transversely, as seen in Fig. 3.

The air is drawn from the exterior of the building, by means of a suitable blower 7, the fan shaft 8 of which may be driven through the medium of a belt 9, and the inlet 10 of which communicates with the atmosphere. The outlet pipe 11 of the blower 7 has its free end entering the inlet opening 3—4 of the tank 1, in order that the current of air created by the blower 7 will be directed longitudinally through the upper portion of the tank.

In order to convey the air from the tank 1, to the room to be supplied with air, a suitable pipe 12 has one end inserted in the outlet opening 3—4 of the tank 1, and is provided at its other end with a register 13 communicating with the particular room to be ventilated. It will be understood, of course, that the outlet pipe 12 may be divided into any number of branches, when a number of rooms are to be ventilated by the present apparatus, and as is well within the province of an ordinary mechanic. It is essential, however, that the cross sectional area of the pipe or pipes 12, be approximately the same as the cross sectional area of the inlet pipe 11 of the tank 1, to thereby avoid a difference in pressure, as would otherwise result, and prove of disadvantage. The air leaving the tank 1 is filtered by means of a screen or reticulated partition 14 secured within the inlet end of the outlet pipe 12.

After the apparatus has been properly set up or applied to the building, as will be obvious, the blower 7 being actuated by any suitable prime mover, will force a current or stream of air through the tank 1 from the pipe 11, the tank serving as a distributing chamber for the air, to deliver the air to the outlet pipe or pipes 12. The air being discharged from the register 13 will ventilate the room to which the ventilator has been applied, whereby the room may be supplied with fresh air to the comfort of the occupants.

When it is desired to humidify the air, the tank 1 is filled with water, so that the level of the water is approximately in the plane

of the lower ends of the openings 3—4, as seen in Fig. 2, the partition or shelf 6 having been removed. Then, as the air passes through the upper portion of the tank 1, the 5 same will skim or brush over the surface of the water, causing waves or ripples to be created upon the surface of the water, due to the eddies created by the current of air. In this manner, the water is evaporated by 10 the current of air, and furthermore, the air will be cooled and purified, to a certain extent, by the waves or ripples of water with which the air eddies contact.

The present apparatus may also be employed for scenting or perfuming the air, this being accomplished by placing the partition or shelf 6 within the tank 1, as illustrated in Fig. 1, and placing upon the partition 6, a quantity of material 15, of any 15 suitable sort, which has the property of scenting or perfuming the air passing thereover or therethrough. The composition 15 which may be natural or artificial, may be such, as to scent the air with the fragrance 20 of various flowers, or blossoms, or the composition 15 may be such as to scent the air with pine, salt or the like. Whatever composition is employed, the air in impinging 25 thereagainst and passing thereover, will be scented or perfumed, which will give the air a natural cooling, curative or other beneficial property or properties. This is particularly desirable when the apparatus is employed for ventilating sick rooms, in order 30 that the patient may be supplied with fresh natural air, as from the pine forests, orange trees, and the like, or in the nature of sea breezes. As seen in Fig. 1, when the scenting or perfuming agent 15 is employed, the 35 lower portion of the tank 1 may also be partially filled with water, to humidify the air also. Instead of disposing the composition or material 15 upon the partition 6, the same 40 may be held within the basket 6'. 45 The present apparatus is an exceedingly inexpensive and simple one, and may readily

be installed in various buildings. The other advantages and capabilities of the present apparatus will be obvious from the foregoing, taken in connection with the drawing, 50 without further or extensive comment being necessary.

Having thus described the invention, what is claimed as new is:—

1. In an apparatus of the character described, a water holding tank having a removable cover and having openings at its ends, a removable partition supported between the ends of the tank and directly below the said openings for holding an air-scenting agent above the water, and inlet and outlet pipes having their ends inserted through the said openings. 55

2. In an apparatus for supplying humidified and scented air, a water holding tank 60 having a removable cover, the ends of the tank and cover having complementing recesses forming openings, seat members secured to the tank directly below the said openings, a removable partition disposed on 70 said seat members for holding an air-scenting agent above the water, and inlet and outlet pipes having their ends inserted through the said openings. 75

3. In an apparatus for supplying humidified and scented air, a tank having a removable cover and openings at its ends, the tank being adapted to hold water, a removable partition supported by the ends of the tank below the said openings for holding an air-scenting agent and for covering the water, inlet and outlet pipes having their ends inserted through the said openings, and a detachable reticulated basket suspended from 80 the cover for holding an air-scenting agent. 85

In testimony that I claim the foregoing as my own, I have hereto affixed my signature in the presence of two witnesses.

FREDRICK W. KALLUSCH.
